UNITED STATES PATENT OFFICE.

WILLIAM G. STOCKHAM AND FRANK L. DOYLE, OF PIQUA, OHIO, ASSIGNEES TO THE STOCKHAM HOMOGENEOUS MIXER MANUFACTURING COMPANY, OF PIQUA, OHIO, A CORPORATION OF OHIO.

MIXING-MACHINE.

No. 873,391.

Specification of Letters Patent.

Patented Dec. 10, 1907.

Application filed August 31, 1906. Serial No. 332,877.

To all whom it may concern:

Be it known that we, WILLIAM G. STOCKHAM and FRANK L. DOYLE, citizens of the United States, residing at Piqua, in the county of Miami and State of Ohio, have invented certain new and useful Improvements in Mixing-Machines, of which the following is a specification.

This invention contemplates certain new and useful improvements in mixing machines and relates particularly to a machine intended for mixing or kneading sand on a foundry floor or the like.

The objects of the invention are to provide novel means for adjusting the mixer or kneader to combine fenders with the machine for throwing the material inwardly and preventing the same from becoming scattered, to provide for agitating the center of the pile or row of material and to insure an effective operation of the mixing or kneading elements thereon.

For a full understanding of the invention and the merits thereof and also to acquire a knowledge of the details of construction of the means for effecting the result, reference is to be had to the following description and accompanying drawings, in which:

Figure 1 is a side elevation, showing the mixer elevated; Fig. 2 is a vertical sectional view showing the mixer in lowered position; Fig. 3 is a plan view; Fig. 4 is a rear view; and, Fig. 5 is a detail perspective view of the gathering blade and its connection with the frame.

Corresponding and like parts are referred to in the following description and indicated in all the views of the drawings by the same reference characters.

The main frame comprises side bars 1 and standards 2, said parts being of any approved construction according to the special design of the machine. Supporting wheels 3 and 4 are provided for sustaining the machine, the front wheels 3 being adjustable to admit of proper steering, whereas the rear wheels 4 constitute drivers to propel the machine forward or backward according to the required direction of movement. The rear wheels 4 are mounted upon spindles or axle arms rigidly connected with the side bars of the main frame and projected outward therefrom. The front wheels 3 are mounted upon spindles attached at their inner ends to vertical posts 5 which are mounted between the outer

ends of horizontal extensions projected outward from hangers 6 and 7 bolted or otherwise attached at their upper ends to the main frame. Arms 8 extend forward from the vertical posts 5 and are connected by means of an arch 9, which in turn has connection with a steering lever 10 or like part for moving the arch laterally when it is required to change the direction of travel of the machine. Each supporting or drive wheel 4 is provided with a gear wheel 11 fast thereto for rotation therewith, power being imparted to the said wheels 4 through the gear wheels 11 from a suitable source of power mounted upon the machine, whether the same be electric or other type of engine commonly employed for operating mechanically propelled road machines. The driving shaft 12 is suitably mounted upon the front portion of the main frame and is connected with the engine or motor in any convenient way so as to be operated therefrom. Each end of the driving shaft is provided with a sprocket pinion 13 and a sprocket gear 14, the elements 13 and 14 being so mounted upon the shaft as to admit of their being thrown into and out of action, a lever 15 being provided for this purpose. A sprocket chain 16 connects each sprocket pinion 13 with the gear wheel 11 on the same side of the machine therewith.

The mixer, kneader or like device for tempering, blending or working the material is preferably arranged at the rear of the machine and comprises a shaft 17, supporting arms 18 and blades 19, the latter being curved longitudinally in an approximately spiral line. The shaft 17 is provided near each end with a sprocket pinion 20 which is connected by means of a sprocket chain 21 with a sprocket gear 14 on the same side of the machine therewith. The mixer is preferably composed of two similar parts or members, each of like formation, the blades of one member inclining in an opposite direction to the blades of the other member and in disposing the members upon the shaft 17, the blades of one are arranged to alternate with the blades of the other. In the operation of the machine as the same travels forward and backward over the material, the latter is moved laterally both outwardly and inwardly with the result that the same is blended so as to produce a homogeneous mass. The shaft of the mixer is mounted in bearings attached to beams 22 which are

pivoted at their front ends at 23 to the side bars 1. The pivoted beams 22 are vertically adjustable at their rear ends, thereby admitting of elevating the mixer to the required position or throwing the same entirely out of action. For convenience of adjusting the pivoted beams and the mixer, a transverse shaft 24 is mounted in bearings at the upper ends of the standards 2 and is provided with a crank handle 25 and with a ratchet wheel 26 and coöperating pawl 27 to hold the shaft against backward rotation. A spool 28 is fast to each end portion of the shaft 24 and a cord, chain or the like 29 is fast at one end to said spool so as to wind thereon, and its opposite end is connected to a pivoted beam 22. Upon rotating the shaft 24 to wind up the cords, chains or like flexible connections 29, the rear ends of the pivoted beams are elevated and the mixer correspondingly lifted.

Bars 30 are pivoted at their front ends to the beams 22 and their rear ends curve downward and are provided with plates 31 which incline rearwardly and inwardly so as to gather or move the material inward in the rear of the mixer. The pivoted bars 30 and beams 22 have independent movement, thereby providing for independent movement of the mixer and gathering blades. A loop-shaped guide 32 is provided at or near the rear of each pivoted beam 22 and the rear portion of a pivoted bar 30 passes therethrough and is held in place and directed in its vertical movements thereby. A spring 33 is arranged within each loop-shaped guide 32 and exerts a downward pressure upon the pivoted bar. Each of said springs is stiffened by means of a rod 34 passed loosely therethrough and through an opening in the upper end of the guide 32. The standards 2 are approximately of inverted V-form and the pivoted beams 22 are located exterior thereto. The foremost leg or member of each standard 2 is provided with a guide bar 35 between which and the said member a pivoted beam 22 passes. A keeper 36 is provided upon the rear leg or member of each standard 2 to limit the upward movement of the pivoted beams.

A suitable motor 37 is mounted upon the main frame of the machine and is operatively connected in any manner with the driving shaft 12 to propel the machine. The drive wheels 4 have a comparatively slow movement imparted thereto, whereas the mixer is driven at a relatively high rate of speed, and as a result, the material is blended or rapidly worked as the machine slowly travels thereover, both in a forward and in a backward direction. The machine in its first operation advances over the material which is thrown upon the floor or gang-way in a pile along the length thereof. When the machine reaches the end of the pile in one direction, the motor is reversed and the machine

caused to traverse the pile in an opposite direction by a backward movement. Usually one movement of the machine over the pile is sufficient for working the material, but should the working not be sufficient to effect the desired result, it is to be understood that the machine may be caused to travel backward and forward over the material as often as necessary in order to attain the desired result.

The numbers or parts comprising the mixer or kneader are usually spaced apart a short distance and in order that the center of the pile may be agitated and moved within the path of the mixer, a divider 44 is provided and arranged in advance of the mixer and opposite the space formed between the inner ends of its members or parts, said divider consisting of a standard provided with a shovel and of such construction as to readily pass through the material and move the same laterally.

Having thus described the invention, what is claimed as new is:

1. In a machine of the character set forth, the combination of a main frame embodying standards, supporting wheels constituting drivers, beams pivoted at their ends to said frame, a rotary mixer journaled upon said pivoted beams, adjusting means between the pivoted beams and standards for entirely raising and lowering the mixer relative to said standards and securing the same in an adjusted position, a drive shaft journaled upon the main frame, connections between the driving shaft and the aforesaid driver and mixer, and a motor mounted upon the machine and connected with the driving shaft to impart motion thereto.

2. In a machine of the character described, the combination of traveling wheels, a framework supported thereby, a rotary mixer revolubly mounted in the framework and embodying laterally extending spirally curved blades, means for revolving said mixer, gathering blades carried by and movable with said support and extending to the rear of the mixer, said gathering blades extending inwardly towards each other, whereby they will tend to move the material inwardly towards the pile and prevent scattering thereof, and yielding means for holding the gathering blades to their work, and permitting a limited vertical play thereof independent of the mixer.

3. In a machine of the character set forth, the combination of a main frame, pivoted beams connected thereto, a rotary mixer mounted upon the pivoted beams, bars pivotally mounted upon said beams, gathering blades attached to the rear ends of the pivoted bars for moving the material inward, and directing and yielding means between the pivoted bars and pivoted beams.

4. In a machine of the character set forth,

the combination of a main frame, beams pivoted thereto and provided with guides, a rotary mixer mounted upon the pivoted beams, bars pivoted to said beams and provided with gathering blades and directed in their movement by the aforesaid guides, and tension springs interposed between the said guides and pivoted bars.

In testimony whereof we affix our signatures in presence of two witnesses.

WILLIAM G. STOCKHAM. [L. S.]
FRANK L. DOYLE. [L. S.]
